CLAIM

The ornamental design for the inflatable pedal kayak, as shown and described.

DESCRIPTION

FIG. 1 is a perspective view of an inflatable pedal kayak design showing my new design.

FIG. 2 is a top view of the inflatable pedal kayak.

FIG. 3 is a bottom view of the inflatable pedal kayak.

FIG. 4 is a left side view of the inflatable pedal kayak.

FIG. 5 is a right side view of the inflatable pedal kayak.

FIG. 6 is a front view of the inflatable pedal kayak; and,

FIG. 7 is a rear view of the inflatable pedal kayak.

Any shading and cross-hatching are not features of the design but are utilized to illustrate the surface contours of the inflatable pedal kayak design in the drawings.

The broken lines depict portions of the inflatable pedal kayak that form no part of the claimed design.
